Primary Examiner — Robert M Spear(74) *Attorney, Agent, or Firm* — Wood, Phillips, Katz, Clark & Mortimer(57) **CLAIM**

The ornamental design for a dispensing closure, as shown and described.

DESCRIPTION

FIG. 1 is an isometric view, taken from the front and right side, of a dispensing closure, showing our new design; FIG. 2 is an isometric view taken from the front and left side thereof;

FIG. 3 is an isometric view taken from the rear and left side thereof;

FIG. 4 is a left side isometric view thereof;

FIG. 5 is a top plan view thereof;

FIG. 6 is a front elevational view thereof;

FIG. 7 is a right side elevational view thereof, the left side elevational view thereof being a mirror image; and,

FIG. 8 is a rear elevational view thereof.

The undisclosed bottom view is unornamented.
